MUSICAL WIND INSTRUMENT

Cosimo Lisi and Ugo Casaccia, Turin, Italy

Application January 9, 1948, Serial No. 1,344
In Italy January 11, 1947

8 Claims. (Cl. 84—388)

1

This invention relates to wind instruments, more particularly to the control device for the air paths, said control being effected by means of valves mounted for axial displacement in a casing, the axes of said valves being arranged parallel to one another in the vertical longitudinal plane of symmetry of said casing.

An object of this invention is to provide a compact wind instrument without any elements protruding laterally from said plane of symmetry, by incorporating at least one of the valve slides into its associated control valve.

A further object of this invention is to provide in a wind instrument of the character specified above a valve slide incorporated into its associated valve, made up of two telescoping parts, means being provided for adjusting from the outside the length of said valve slide.

A further object of this invention is to provide a wind instrument of the type comprising three valves and three valve slides controlled by said valves, in which the shortest valve slide is incorporated into the intermediate valve, while the other two valve slides are fitted coaxially to the opposed ends of the casing enclosing the valves and are symmetrically arranged with respect to the longitudinal vertical plane containing the valve axes.

A further object of this invention is to provide in an instrument of the type specified above, valve slides in the form of tubes of oval section or twin tubes in order to decrease in height the inlet and outlet ports of said valve slides in the direction of movement of the valves, thereby reducing the stroke of said valves for switching over the various valve slides.

The invention will be better understood from the following description and drawings referred to therein, in which:

Figure 1 is a front elevation, partly in section, showing a unit with piston pumps for the control of the wind pipes;

Figures 2 and 3 are an end elevation and a view from above, respectively;

Figure 4 is a view similar to Figure 2, showing the invention in connection with a control unit of the type mentioned in the premises;

Figure 5 is an elevation, partly in section, of a conventional control unit embodying plugs rotatable within a socket;

Figures 6 and 7 are a cross section and a plan view showing the use of flattened tubes in connection with the unit shown in Fig. 5;

Figure 8 shows the switch-over plug;

Figure 9 is a plan view showing the twin pipe construction.

2

In the construction shown in Figures 1 to 3, 1 denotes the single round pipe extending from the mouth-piece of the instrument and 2 is the coaxial pipe extending to the bell. The pipes 1 and 2 are bifurcated into two pipes 1', 2', respectively, of smaller diameter, but of which the area as a whole equals the area of pipes 1 and 2. The twin pipes 1', 2' end at pairs of holes bored at the opposite ends of the casing 3 of the valves, 10 having in its inside intermediate walls 4 forming the seatings in which move the valves 5, 6, 7 pushed upwardly by springs 10 and stopping in their position of rest against the cover 3'. In the walls 4 are bored pairs of holes 8 and 9 in alignment with the pairs of twin pipes 1', 2' with which the pairs of transverse twin pipes 5', 6', 7' located within the various valves are aligned in their inoperative position, so that direct communication is established between pipes 1 and 2. 20 Two of the usual valve slides *a* and *b* more particularly a full length and a mean length one are arranged at the opposite ends of the casing 3 and when they are connected in the circuit, they serve for varying the pitch of the sound emitted by 25 the instrument. These valve slides are similarly in the form of twin pipes 11 and 11' and end each at four holes 12 and 12' bored in the wall of the casing 3. The third and shorter valve slide *c*, still in the form of twin pipes 13, 13a, is arranged 30 within the intermediate valve slide 6. The portion 13a of this valve slide is slidable on the stationary portions which ends below at holes cut in the wall of the valve 6, while the slidable portion is fixedly connected with a screw-threaded plug 14 screwed in a central tapped bore in the end knob 15, which is rotatably mounted, but kept against displacement, at the top of valve 6. Such an arrangement by which the shortest valve 35 slide *c* is incorporated in the valve 6 by which it is controlled, sharply distinguishes over the arrangements used heretofore, in which the valve slide arranged externally of the casing 3, is, like the other, rather cumbersome. Moreover, the possibility of micrometric adjustment of its 40 length from the outside, permits sharp tuning of the instrument. The valve slides in the form of twin tubes are symmetrically arranged on opposite sides of the middle transverse plane containing the valve axes. The valves 5 and 7 are 45 formed with inner passages 16 of S-shape and semicircular passages 17, all in the form of twin tubes. 50

The device operates as follows:

When all the valves are at rest, i. e., in their 55 lifted position, the wind follows the direct path through passages 5', 6', 7'. When a valve, for

instance the valve 5, is lowered, the associated valve slide *a* is connected, for the passages 17 establish communication between the twin tubes 1' and inlet to the valve slide *a* and passages 16 establish communication between the outlet of the valve slide and holes 8, as clearly shown in dotted lines in Figure 1. Through the adoption of twin tubes, each of a considerably smaller diameter than a single conventional tube, the piston stroke is reduced to about one half.

Figure 4 shows the use of the invention in connection with flattened single tube construction.

In said figures the flattened pipes are denoted by 1a', 11a.

It will be obvious that this invention is not limited to the arrangements described above and shown in the accompanying drawing, but may be modified with respect thereto within the scope of the appended claims.

What we claim is:

1. In a wind-instrument the combination with a main conduit and a valve controlling said main conduit, of a valve slide seated in the recess in said valve, the inlet and outlet openings of said valve slide being arranged so as to be inserted into the main conduit when the valve is lowered.

2. In a wind-instrument the combination with a main conduit, and a valve controlling said main conduit, of a valve slide seated in said valve and comprising two parts telescopically connected together, one of said parts being fixed and having its inlet and outlet openings arranged in such manner as to be inserted into said main conduit when the valve is lowered, while the other part is mounted in said valve for axial displacement for adjusting said valve slide in length.

3. In a wind-instrument of a mouth-tube, a bell tube, a plurality of valves, a casing in which said valves are mounted, twin pipes connected to said mouth tube and bell tube, respectively, said twin pipes being fixed to opposite sides of said casing for connecting said mouth tube and bell tube together through twin conduits in said valves, when said valves are in raised position, a long twin valve slide secured to said casing over said mouth tube, a second twin valve slide connected to the casing over said bell tube, said twin valve slides being controlled by the terminal valves, a third shorter twin valve slide seated in the intermediate valve, said twin valve slides being connected between the mouth tube and bell tube, when their associated valve is depressed, the twin pipes, twin valve slides, mouth tube and bell tube being symmetrically arranged with respect to the vertical axis extending through the axes of said valves.

4. Wind-instrument as claimed in claim 3, in which the shorter twin valve slide seated in the intermediate valve is made up of two telescoping stationary and movable portions, respectively, and in which means are provided for adjusting the position of said movable portion.

5. Wind instrument as claimed in claim 3, in which the shorter twin valve slide, seated in the

intermediate valve, is made up of two stationary and movable portions, respectively, and in which a rotatable button is fitted on the outer end of said intermediate valve and kept against axial displacement, said button having a screw-threaded axial bore engaging a screw-threaded pin fast with said movable portion.

6. Wind instrument comprising in combination with three valves, a casing in which said valves are mounted with their axes parallel to one another situated in the vertical plane of symmetry, a mouth-tube and a bell tube arranged coaxial in the lower portion of said casing the axes of said tubes being situated in said plane of symmetry, a valve slide secured to one end of said casing, a second valve slide secured to the other end of said casing, said valve slides having their axes arranged symmetrically with respect to said plane of symmetry, a third valve slide mounted in the intermediate valve so as to be inserted between the said mouth and bell tube when the valve is lowered.

7. In a wind-instrument a mouth-tube, a bell tube, a plurality of valves, a casing in which said valves are mounted, oval pipes connected to said mouth-tube and bell tube, respectively, said oval pipes being fixed to opposite sides of said casing for connecting said mouth-tube and bell tube together through oval conduits in said valves, when said valves are in raised position, a long oval valve slide secured to said casing over said mouth-tube, a second oval valve slide connected to the casing over said bell tube, said oval valve slides being controlled by the terminal valves, a third shorter oval valve slide seated in the intermediate valve, said oval valve slides being connected between the mouth-tube and bell tube, when their associated valve is depressed, the oval pipe, oval valve slides, mouth-tube and bell tube being symmetrically arranged with respect to the vertical axis extending through the axes of said valves.

8. Wind-instrument as claimed in claim 7, in which the shorter oval valve slide seated in the intermediate valve is made up of two telescoping stationary and movable portions, respectively, and in which means are provided for adjusting the position of said movable portion.
